AUTOMATIC MATCH LIGHTER

Christian C. Severin, Unadilla, Nebr.

Application August 21, 1934, Serial No. 740,846

5 Claims. (Cl. 312—82)

My invention relates to automatic match lighters, its object being the provision of a device for dispensing matches one at a time and in lighted condition.

5 Another of my objects is the provision of a device for receiving and holding a box of matches for delivery one at a time into a channel from which the matches are forcibly ejected in the direction of their length and caused to ignite by impact with an abrasive surface.

Another object which I have in view is the provision of a device including a lever for supporting a match, the lever being manually operable to first release the match and then to eject the 15 match.

Another of my objects is the provision of a device for igniting a match by impact with an abrasive surface combined with an automatically operable clamp for releasably holding the match 20 while it is burning.

Having in view these objects and others which will be pointed out in the following description, I will now refer to the drawing, in which

Figure 1 is a view in perspective of my automatic match lighter, portions being broken away to disclose otherwise concealed parts.

Figure 2 is a view in perspective showing the match box holder of my match lighter with a match box in position in the holder.

30 Figure 3 is a vertical sectional view showing particularly the match slot and hole and their relation to the lever for releasing and ejecting a match.

Figure 4 is a view in horizontal section through 35 the base of my device showing particularly the relation between the ejecting lever and the channel through which the match is ejected.

Figure 5 is a view in elevation showing the match holding device and the mechanism for 40 automatically clamping the match.

The base of the device is indicated by the numeral 10. Secured to the base 10 is a wedge block 11 for supporting a match box holder 12. The match box holder 12 is provided with a 45 slot which communicates with a groove 13 in the base 10. As shown in Figure 3 the groove has a rounded bottom for supporting the match while it is being ejected. The groove is substantially of the same length as that of the match or a 50 little longer. The block is also recessed at 14 with an elongated slot at 15, the slot 15 communicating with the recess 14. The slot 15 as shown in Figure 3 passes through the match channel of the block 10. The ejecting lever 16 55 passes through the slot 15 and into the recess 14

where it is anchored at 17. The lever 16 is normally held in the full line position of Figure 4 by means of any suitable spring device such as that shown at 18 in Figure 4. The ejecting lever 16 can thus readily be pulled from its full line position to its dotted line position in Figure 4 but when it is released it snaps instantly into the full line position. 5

The matches are fed one at a time into the groove 13 to rest on the upper edge of the lever 16. When the lever 16 is moved to the dotted line position of Figure 4 the bottom match will be released to fall into the bottom of the groove 13 due to the fact that the lever 16 may be pulled back beyond the rear edge of the match. The 15 spring 18 is sufficiently powerful to forcibly eject the match when the lever 16 is released from its dotted line position. The wall at the discharge end of the groove 13 is partly closed in order to provide a suitable exit 13' through 20 which the match may be ejected and to insure substantially straight line movement of the match when it leaves the groove 13. As the match passes out through the opening 13', its straight line movement is maintained by means of the 25 trough 13a which projects from the base 10.

The match box holder 12 is best shown in Figures 1 and 2. This consists of a base which is secured to the wedge 11. The base is crimped transversely in two places for adjustably positioning the match box clamp 19. Rising from one lateral edge of the base is a side wall 20 which cooperates with the clamp 19 by moving the clamp 19 relative to the base of the match box holder. Any desirable pressure may be obtained between 35 the clamp and the side wall 20. The upper portion 21 of the clamp is slidable in up and down direction relative to the portion 19 of the clamp. In this manner it is possible to provide a clamping action against the match box between the 40 clamp portion 21 and the base of the match box holder. The match box 22 is thus firmly clamped in the match box holder. It should be noted that the wall 20 is partly broken away in the Figure 1 view in order to more clearly disclose the clamp- 45 member 19.

As shown in Figure 2 the side wall 20 is provided in its middle with a cutaway portion. When the match box is clamped into the holder as shown in Figure 2 a portion of the roughened surface of the match box is thus exposed at 23. When it is desired to strike a match in the usual manner it will be found that ample roughened surface is exposed for this purpose.

The exit 13' of the slot 13 will guide the out- 55

ward movement of the match as it is being forcibly ejected when the lever 16 is released. The matches are so positioned that they leave the slot 13 with the head end first. Their movement 5 is substantially in a straight line. For lighting the matches I provide a lighting surface 24 in the direct path of the match 25 as it is shot out through the exit 13'. This lighting surface 24 may be of any suitable form such as a plurality 10 of serrated blades secured to a base. A lip 26 projects downwardly and rearwardly from the base as shown in Figure 1. The base with its serrated blades 24 is supported in position by means of a frame 27 which is secured to the base 15 10 to project therefrom.

Means are also provided for grasping the match 25 at the moment that it strikes the lighting surface 24. These means include a clamp comprising stationary jaws 28 and movable jaws 29. 20 This clamp is secured to the frame 27 in a position such that the match is shot through the clamp. It is therefore necessary that the jaws 29 be moved to closing position at about the time when the match head strikes the lighting surface 24.

The jaws 29 are secured to a leaf which in turn is secured to the slotted lever 30. An irregularly curved lever 31 is journaled at 32 and thus secured to the frame 27. The curved lever 31 has 30 a curved free end portion which travels in the slot of the lever 30. The pivotal movements of the lever 31 are thus communicated to the lever 30 to move the jaws 29 toward or away from clamping relation with the fixed jaws 28. In the 35 position shown in Figure 5 the jaws are spaced to permit the passage of the match but as shown in Figure 1 the jaws are in closed position to hold the match. The jaws 28 and 29 are made of a light resilient material so that the match 25 may 40 be easily removed.

The irregularly curved lever 31 is provided with an aperture 33 for receiving a rod 34 which is connected to the lever 16 and movable thereby whenever the lever 16 is moved. The rod 34 has 45 an outwardly curved end which engages the lever 31 at the time when the lever 16 has been drawn back a sufficient distance into the dotted line position of Figure 4. Further movement of the lever 16 then causes movement of the lever 31 to 50 move the jaws 29 to open position. The lever 16 then reaches its extreme position as shown in dotted lines in Figure 4 from which it may be released suddenly to eject the match. At this time the jaws 28 and 29 are in the open position 55 shown in Figure 5 but these jaws must be closed at about the time when the match strikes the lighting surface 24. The rod 34 is provided with a stop 35 which suddenly engages the lever 31 when the lever 16 is released. The blow imparted 60 to the lever 31 by the stop 35 causes the movement of the lever 31 to close the jaws 29 against the fixed jaws 28.

The tray 36 is positioned underneath the clamping device 28-29 and the match lighting 65 device 24. The tray is designed primarily for the reception of burnt matches but it will also receive sparks which might otherwise cause damage. Should the clamp fail to retain the match 70 after it is lit, the match will fall into the tray. The tray 36 is removable to facilitate the removal of its contents and for this purpose it is provided with a wire frame 37 which may be releasably secured to the base 10.

75 My automatic match lighter is designed pri-

marily for use in stores where cigars and tobacco are sold. The entire box of matches is placed in position on the match box holder and is clamped thereto by sliding the clamping members 19 and 21 into clamping engagement with the box. The 5 matches will tend to fall into the groove 13 where they will rest on the lever 16. The movement of the lever 16 to its dotted line position in Figure 4 will allow one match to drop into the path of the lever so that when the lever is released it will 10 engage the rear end of the match to eject it forcibly through the aperture 13'. The match clamp being open at the time, the forward portion of the match will pass through the clamp. In positioning the match box on the match box 15 holder 12, care should be taken to be sure that the match heads are at their forward ends during ejection. The impact of the match head with the lighting surface 24 causes the match to light but at the same time the adjustable stop member 20 35 engages the lever 31 to close the jaws of the match clamping device. At this point the match will be clamped at its rear end and it will be burning and ready for delivery. Since the clamping members 28 and 29 are made of light and 25 resilient material, the match 25 can be easily withdrawn from the clamp. The parts are then ready for the delivery of another match by movement and release of the lever 16. Should the lever 16 be actuated before the burning match 25 has 30 been removed, the automatic opening of the clamping jaws will cause the match 25 to drop into the tray.

It is very seldom that a match will fail to ignite when it strikes the surface 24. If it does fail to 35 ignite, it may simply be removed from the clamp and ignited in the usual manner against the roughened surface 23 of the match box 22.

Having thus described my invention in such full, clear, and exact terms that its construction 40 and operation will be readily understood by others skilled in the art to which it pertains, what I claim as new and desire to secure by Letters Patent of the United States is:

1. In an automatic match lighter, a base having 45 a groove for receiving matches, means adapted to act against the rear extremity of a match for forcibly ejecting the match in the direction of the length of the groove, a match lighting member interposed in the path of the match 50 whereby the match will be ignited by impact against said match lighting member and clamping means between the lighting member and the base for releasably holding the match.

2. In an automatic match lighter, a base having 55 a groove for receiving matches, means adapted to act against the rear extremity of a match for forcibly ejecting the match in the direction of the length of the groove, a match lighting member interposed in the path of the match whereby 60 the match will be ignited by impact against said match lighting member, and a clamp disposed between the lighting member and the base for engaging the rear portion of the match.

3. In an automatic match lighter, a base and 65 a match box holding frame secured thereto, said base having a groove for receiving the matches from the match box in said match box holding frame, the groove in said base being open in one of its extremities, a spring pressed lever in said 70 base and positioned transversely in the groove thereof, said lever being movable beyond the rear extremity of the lowermost match in the groove whereby release of said lever will forcibly eject the match from the groove through the open ex- 75

tremity thereof, means active when the lever has reached a predetermined position in the ejecting operation for releasably clamping the match, and means for stopping and igniting the match.

5 4. In an automatic match lighter, a base and a match box holder secured thereto, clamping members on said holder for clamping a match box in inclined relation to said base for gravity feed of the matches therefrom, said base being 10 provided with a groove for receiving the matches from the match box, a spring actuated lever for forcibly ejecting the matches headfirst from said base in the direction of the length of the groove thereof, a match lighting member in the 15 path of the ejected match whereby the impact of

the match head with said match lighting member will cause the match to ignite and means active when the lever has reached a predetermined position in the ejecting operation for releasably clamping the match.

5 5. In an automatic match lighter, a match lighting member, means for forcibly discharging a match headfirst in the direction of its length to be ignited by impact with said match lighting member, and means for engaging the rear portion of the match while it is being ignited and for releasably holding the match, said latter means being inactive until the match has been ejected by said first means.
